UNITED STATES PATENT OFFICE.

EDWARD E. CLAUSSEN, OF HARTFORD, CONNECTICUT.

HAT.

1,250,968.

Specification of Letters Patent. Patented Dec. 25, 1917.

Application filed September 5, 1916. Serial No. 118,349.

To all whom it may concern:

Be it known that I, EDWARD E. CLAUSSEN, a citizen of the United States, residing at Hartford, in the county of Hartford and 5 State of Connecticut, have invented certain new and useful Improvements in Hats, of which the following is a specification.

This invention relates to hats, the principal object of the invention being the provision of a light yet comparatively strong article of the kind in question which is susceptible of inexpensive manufacture and which is primarily intended for temporary use. The low expense I prefer to secure by 10 15 making the hat of paper material. There are probably other equivalent materials which would subserve my purpose as well, but paper has been found quite satisfactory. The hat while really intended for temporary 20 25 use, is thoroughly practical for comparatively long wear. It may be of any desirable shape; for instance it may be fashioned after the ordinary summer or straw hat and be worn by either sex.

25 In the drawings accompanying and forming part of the present specification I have shown in detail one convenient form of embodiment of the invention which I will set forth fully in the following description. I 30 do not limit myself to this disclosure; I may depart therefrom in several respects within the scope of the invention defined by the claims following said description.

Referring to said drawings:

35 Figure 1 is a side elevation, and

Fig. 2 is a bottom plan view of the crown portion or member of the hat.

Fig. 3 is a top plan view of the brim portion.

40 Fig. 4 is a top plan view of the finished hat.

Fig. 5 is a side elevation of the same with a portion broken away and in section.

Like characters refer to like parts throughout the several views.

The hat as I have already observed may be of any suitable shape. In that form of embodiment of the invention which is represented in the drawings, it resembles closely 50 the familiar straight brimmed straw hat. It comprises a suitable crown and a suitable brim, generally made separate and of different grades of paper or analogous material. For instance, the crown can be made of comparatively light or thin paper, while the 55 brim can be made of heavier stock. While

this is illustrative merely, it is a highly advantageous and therefore, preferable relation. The crown and the brim are united in some desirable manner, for instance one of them may be provided with several tabs or ears adapted for suitable connection as by some convenient adhesive, to the other. I also prefer that one of these two parts be plaited, if not wholly at least one part. 60 65 This is not only an effective construction, but the plaiting or creasing adds strength. Preferably the crown is plaited or creased. With the foregoing general remarks I will now refer more in detail to what is illustrated in the several views of the drawings.

The hat shown comprises in its make-up a brim as 2 and a crown as 3. This brim is preferably made of some comparatively heavy paper stock such as cardboard, which 70 75 possesses a certain amount of stiffness without undue resilience, although owing to its character, it can naturally be bent. As shown the brim has a central opening 4 practically oval in form or of a shape to 80 agree approximately with the outline of the base portion of the coöperating crown, which in this case would be that already referred to. This crown comprises a top as 5 and a wall portion as 6, the wall portion being 85 plaited and being in the present case integral with the top. The crown can be made in one piece and the body or wall portion 6 thereof can be plaited with the aid of a suitable machine or dies. The top is flat, while the wall or body portion 6 is tapered or frusto-conical, the slope being upwardly and inwardly. This plaiting or creasing of the body or wall portion of the top naturally 90 increases its strength, although in some 95 cases the top might be perfectly plain. The plaited construction has, as I observe, its utility, especially when the crown is made of comparatively light material. There is an advantage in tapering the crown of the 100 hat, in that the hats can be easily nested and thus save space in shipping.

In the construction shown the lower edge of the bell-like crown 3 fits flatwise against the brim 2 around the central opening 4 105 thereof, the opening of the crown being in register with the opening 4. From the wall of said opening 4 there project tabs or ears as 7 integral with said brim and which as shown are in quite large number and somewhat close together. The sides of these tabs converge inwardly.

To assemble the crown 3 and brim 2 the following procedure may be adopted: A suitable adhesive will be applied to the upper surfaces of the several tabs 7, following 5 which the crown will be placed on the upper surface of the brim with the opening of the crown in register with the brim opening 4, the bottom of the crown being of such dimensions as to overlie slightly the brim 10 around the opening therein to bring the inner bottom surface of the crown practically flush with the wall of said opening 4. After this is done, the several tabs 7 will be upset at practically right angles to the brim and 15 will be fastened by the adhesive already applied thereto to the inner surface of the crown. When the adhesive is set the two members will be firmly united together.

To finish the hat I may apply to it exteriorly of the crown at the base thereof a band 8. This band is also of paper and it can be held in place in any convenient manner as by a fit.

To strengthen or reinforce the brim it may 25 be beaded, there being as shown four of such beads as 9. This beading can be accomplished by compressing the stock, the beads being on the upper surface of the brim, while the under surface is correspondingly 30 grooved. The beads as illustrated follow virtually the external shape of the brim and they are separated to provide openings as 10 for the escape of any water between them and the crown. Preferably all parts of the 35 hat are waterproofed, for instance by paraffin or some other suitable substance, both internally and externally, so that the article can with comparative safety be worn in wet weather.

40 I have shown four beads on the brim. The

number is not a matter of consequence, nor is their form essential, although the arrangement shown is a very good one. In fact the beads when in a row might be duplicated, or they can be disposed in ways other than that shown. As a matter of fact the invention is not restricted as to these and other points. 45

What I claim is:

1. A hat comprising a paper crown and 50 a paper brim, the crown having a top and a wall portion, the wall portion being plaited and united to the brim.

2. A hat comprising a paper crown and 55 a paper brim, the stock of the crown being lighter than that of the brim, the crown having a top and a wall portion, said wall portion being plaited and the brim having a plurality of upstanding tabs united to the interior of the brim.

3. A hat comprising a crown and a brim 60 both of paper, the crown being of lighter stock than the brim and having a top and a wall portion, the latter being plaited, the brim having a succession of beads spaced 65 from each other.

4. A hat comprising a crown and a brim 70 both of paper, the crown being of lighter stock than the brim and having a top and a wall portion, the latter being plaited, the brim having a succession of beads spaced from each other and the crown having a paper band thereabout.

In testimony whereof I affix my signature in the presence of two witnesses.

EDWARD E. CLAUSSEN.

Witnesses:

L. L. MARKEI,
HEATH SUTHERLAND.
